UNITED STATES PATENT OFFICE.

CHARLES T. WAGNER, OF COLLEGE POINT, NEW YORK.

DESIGN FOR QUILTING.

SPECIFICATION forming part of **Design No. 18,403**, dated June 19, 1888.

Application filed January 31, 1888. Serial No. 262,591. Term of patent 7 years.

To all whom it may concern:

Be it known that I, CHARLES T. WAGNER, of College Point, Queens county, State of New York, have originated and produced a new 5 Design for Quilting, of which the following is a specification.

My design relates to quiltings which are manufactured for linings for skirts, for garments, and for bed-coverings.

10 The design consists in the combination of rows of pairs of intersecting circles, other rows of pairs of intersecting circles arranged opposite the spaces between the intersecting circles of the rows first mentioned, and pairs of figures 15 connecting the pairs of intersecting circles.

The accompanying drawing is a view of a piece of quilting ornamented with my design.

15 a' a^2 designate circles. Each circle a' intersects the adjacent circle a^2 , so that a pair of intersecting circles is formed. The pairs of intersecting circles a' a^2 are arranged in rows.

20 a' a^2 designate other pairs of similar intersecting circles. These intersecting circles a^3 a^4 are likewise arranged in rows, but are so disposed as to be opposite the spaces between the 25 pairs of intersecting circles of the rows a' a^2 .

b' represents figures shown as bracket-like figures extending between the circles a' and the circles a^2 . b^2 are similar figures connecting the circles a^2 with the circles a^4 . It will 30 be seen that the figures b' b^2 are arranged in pairs. It will be seen that all the rows of pairs of intersecting circles are connected together by these figures.

What I claim as new, and desire to secure 35 by Letters Patent, is—

The design for quilting, consisting of the combination of rows of pairs of intersecting circles, other rows of pairs of intersecting circles arranged opposite the spaces between the 10 intersecting circles of the rows first mentioned, and pairs of figures connecting the pairs of intersecting circles, whereby large and small figures are produced, each small figure being 15 between two large figures and conversely, substantially as shown and described.

CHAS. T. WAGNER.
